NO. 2945

Part consisting in Niches, Reliefs, Design for Clock Case, etc.

Drawn by
John M. Williams

PATENTED
MAR 3 1888

John M. Williams

United States Patent Office.

CARL MÜLLER, OF NEW YORK, N. Y.

Design No. 2,943, dated March 3, 1868.

DESIGN FOR A CLOCK-CASE.

The Schedule referred to in these Letters Patent and making part of the same.

TO ALL WHOM IT MAY CONCERN:

Be it known that I, CARL MÜLLER, of the city, county, and State of New York, have invented a new and ornamental Design for Clock-Case; and I do hereby declare that the following is a full, clear, and exact description thereof, which will enable those skilled in the art to make and use the same, reference being had to the accompanying drawing, forming a part of this specification, in which—

Figure 1 represents a front elevation of the design.

Figure 2 is a side elevation of the same.

Figure 3 is a transverse vertical section of fig. 1.

This invention relates to a design for a clock-case, said design consisting mainly of two parts, the base or pedestal B, and the case proper, C.

The pedestal or base, B, is embellished by rich arabesques, as shown in figs. 1 and 2. On it is the case proper C, the upper part of which is in the shape of a horse-shoe arch, A, (which contains the dial-hole,) supported by two columns E E, one on each side. The arch A in the front is composed of small rectangular or trapezoids B, alternately raised and sunk, each of these rectangles containing ornaments, as shown in figs. 2 and 1. The space under the dial-hole, and between the two columns, is decorated by an eagle's head in bas-relief, surrounded by ornaments and foliage, as shown in fig. 1. The arch A is embellished by a top ornament, T, which consists of a staff surmounted by a star, ornaments, as seen in fig. 1, growing out of said staff. The sides of the case C and base B are ornamented, as shown in fig. 2, and are at right angles to the front.

What I claim as new, and desire to secure by Letters Patent, is—

The design for a clock-case, as herein shown and described.

CARL MÜLLER.
